UNITED STATES PATENT OFFICE

2,069,498

OIL BURNER TIP

Walter B. Lang, Steelton, and John C. Wohlfarth, Harrisburg, Pa., assignors to Bethlehem Steel Company, a corporation of Pennsylvania

Application May 25, 1935, Serial No. 23,348

5 Claims. (Cl. 299—120)

This invention relates to liquid fuel burners and more particularly to the nozzle and its nebulizing details thereof.

It is the particular object of our invention to provide a nozzle in which the nebulizing elements are specifically designed to ideally spray the liquid fuel for its function as a heating medium in such a manner that the formation of carbon on the exposed end of the nozzle when in use is practically eliminated.

It is another object of our invention that the parts comprising the nozzle shall be economical to manufacture, easy to clean, and readily assembled and disassembled.

15 Other objects and advantages will be apparent from the following description, wherein reference is made to the accompanying drawing illustrating the preferred embodiment of our invention, and wherein similar reference numerals designate similar parts throughout the several views.

Fig. 1 is a longitudinal sectional view through the nozzle and the nozzle end of the burner pipe;

25 Fig. 2 is an outer end elevation of the clamping nut; and

Fig. 3 is an outer end elevation of the nebulizer.

Referring now to Fig. 1 of the drawing, the burner nozzle 10 has a threaded engagement 11 with the end of a liquid fuel supply pipe 12. The nozzle 10 comprises a clamping nut 13 of substantially cylindrical form having its pipe end 14 formed as a hexagon as shown in Fig. 2 and is further provided with a counterbore 15, a portion of which is internally threaded for the aforementioned threaded engagement 11, and a bore 16 at its front end. An annular recess 17 on the front face 18 communicates with the counterbore 15 through passageways 19. The front end is threaded externally for a threaded engagement 20 with the nebulizer nut 21.

40 The nebulizer nut 21 is preferably manufactured from a hexagon bar and is counterbored from the rear to provide for an internal thread for the aforementioned threaded engagement 20, and is provided at its front end with a bore 22, and is further provided with an annular recess 23 machined at the inner end of the internal thread to form a flange 24 having a rearwardly facing seat 25.

50 A burner tip 26 of general cylindrical form has a flanged portion 27 formed by a portion 28 of reduced diameter extending forwardly through the bore 22 of the nebulizer nut 21. The portion 28 extends outwardly beyond the forward end of nebulizer nut 21 so that its face 29 is an appre-

ciable distance forward thereof, and is preferably beveled off at its corner 30 to the depth of its overextension. The forward face 31 of the flanged portion 27 is carefully machined to form a seal when in engagement with the face 25 of the nebulizer nut 21, while the rear face 32 thereof is carefully machined at its outer portion to a bevel face 33. The burner tip 26 is counterbored from the rear to such diameter and depth that it becomes a cupped shell having an inner cylindrical wall 34 and an inner transverse wall or face 35. The disc-like wall formed between the outer face 29 and the inner face 35 is provided with an aperture 36 enlarged conically at its inner end as at 37.

5 A nebulizer 38 is a cylindrical flanged plug in general form having a forward plug-like portion 39 of reduced diameter, a flanged portion 40, and a rear plug-like portion 41 of reduced diameter. The rear face 42 of the flanged portion 40 is preferably concaved slightly so as to assure 10 of a leak-proof seal at its outer diameter when in engagement with the face 18 of the clamping nut 13. The forward face of the flanged portion 40 is cupped out to form an annular recess 43 surrounding the inner end of the portion 39, and comprises an outer transverse face 44 of nearly 15 knife-edge proportions, a frusto-conical face 45, an inner transverse face or bottom 46, and the inner end of the cylindrical wall 47 formed by the reduced diameter portion 39. A series of longitudinal apertures 48 pierce the flanged portion 40 in uniform circumferential spacing—the said 20 apertures 48 being conically enlarged toward the face 42. The circumferential spacing of the apertures 48 is such that when in assembled 25 relation therewith they are in opposed relation thereto the annular recess 17 of the clamping nut 13. The forward face 49 of the portion 39 has formed therein the recess 50 from which 30 radiate the tangential grooves 51.

35 When assembled the relationship of the burner tip 26 to the nebulizer 38 is such, that the inner face 35 and the bevel face 33 of the burner tip 26 contact simultaneously and respectively the forward face 49 and the frusto-conical face 45 of the nebulizer 38, and in this manner 40 passageways are formed by the tangential grooves 51 communicating the passageway 52 with the aperture 36. The passageway 52 is an 45 annular and is formed by having the diameter of the forward plug-like portion 39 of the nebulizer 38 smaller than that of the diameter of the wall 34 of the burner tip 26. At the same time the recess 43 forms an annular passageway com- 50 55

municating the apertures 48 with the passage-way 52.

When in the proper assembled relation shown in Fig. 1, tightening of the threaded engagement 20 between the clamping nut 13 and the nebulizer nut 21 results in a clamping action between the forward face 18 of the clamping nut 13 and the seat 25 of the nebulizer nut 21, which, by reason of the interposed parts—the burner tip 26 and the nebulizer 38, together with their inter-fitting relation as hereinbefore described, further results in a leak-proof condition throughout the nozzle 10—liquid can issue only at its intended aperture 36. In order to assure that the proper leak-proof seal is secured between the bevel face 33 of the burner tip 26 and the conical seat 45 of the nebulizer 38; a slight clearance is provided for between the bore 22 of the nebulizer nut 21 and the circumferential 15 wall of the portion 28 of the burner tip 26 and between the bore 16 of the clamping nut 13 and the circumferential wall of the portion 41 of the nebulizer 38. This clearance compensates for mal-adjustment of centering of the respective parts due to manufacturing variations.

When in use liquid fuel under pressure is forced through the liquid fuel supply 12 and on through the burner nozzle 18 through the communicating passageways hereinbefore described 30 until it emerges in the form of nebulized spray from the aperture 36.

It will be apparent to those skilled in the art that we have shown a specific type of nozzle, and that we have described and illustrated its various features in considerable specific detail for illustrative purposes, but we do not wish to be so limited, but may use such modification in, substitution for, or equivalent thereof, as are embraced within the scope of our invention or as 35 pointed out in the claims.

Having thus described our invention what we claim as new and desire to secure by Letters Patent is:

1. A liquid fuel nozzle comprising a body with 45 an exit, a nebulizer having a flanged portion overlying said body and having a passage communicating with said exit, and a forward hublike portion having a recess communicating with said passage by means of tangential grooves, a tip overlying said forward portion and having a discharge port in communication with said recess, and means for uniting the recited parts.

2. A liquid fuel nozzle comprising a body with 55 an exit, a nebulizer having a flanged portion overlying said body and having a passage communicating with said exit, and a forward hublike portion comprising an end face and a peripheral wall, a recess in said face, and a peripheral wall, a tip having a discharge port overlying said recess and a recess to the rear thereof and in communication therewith into which the said forward hublike portion extends, said second mentioned recess being of larger diameter than that of the said forward hublike portion whereby a passageway is formed 60 communicating said tangential grooves with said passage, and means for uniting the recited parts.

3. A liquid fuel nozzle comprising a body having an inlet, an exit, and a centering bore, a nebulizer having a rear portion centered in said centering bore, a central flanged portion overlying said body and having a passage communicating with said exit, and a forward hublike portion comprising an end face and a peripheral wall, a recess in said face, and tangential grooves communicating said recess with said peripheral wall, a tip having a discharge port 10 overlying said recess and a recess to the rear thereof and in communication therewith into which the said forward hublike portion extends, said second mentioned recess being of larger diameter than that of the said forward hublike portion whereby a passageway is formed 15 communicating said tangential grooves with said passage, and means for rigidly securing tip, nebulizer, and body in assembled position.

4. A liquid fuel nozzle comprising a body having an inlet, an annular exit, a plurality of passageways communicating said inlet with said annular exit, and a centering bore, a nebulizer having a rear portion centered in said bore, a central flanged portion overlying said body having an annular recess on its forward face and a plurality of passageways communicating said annular recess with said annular exit, and a forward portion comprising an end face and a peripheral wall, a recess in said face and tangential grooves communicating said recess with said peripheral wall, a tip having a discharge port 20 overlying said recess and a recess to the rear thereof and in communication therewith into which the said forward hublike portion extends, said second mentioned recess being of larger diameter than that of the said forward hublike portion whereby a passageway is formed 25 communicating said tangential grooves with said annular recess, and means for rigidly securing 30 tip, nebulizer, and body in assembled position.

5. A liquid fuel nozzle comprising a body having an inlet, an annular exit, a plurality of passageways communicating said inlet with said annular exit, and a centering bore, a nebulizer having a rear portion centered in said bore, a central flanged portion overlying and in engagement with said body having an annular recess with a beveled peripheral wall on its forward 45 face and a plurality of passageways communicating said annular recess with said annular exit, and a forward portion comprising an end face and a peripheral wall, a recess in said face and tangential grooves communicating said recess with said peripheral wall, a tip having a discharge port 50 overlying said recess, a recess in communication with said port into which the said forward portion extends whereby a passageway is formed communicating said tangential grooves with said annular recess, a rear flanged 55 portion beveled on its rear outer periphery engaging said beveled peripheral wall, and the end wall formed by said second mentioned recess overlying and in engagement with said end face, and means for rigidly securing tip, nebulizer, 60 and body in assembled position.
